UNITED STATES PATENT OFFICE

108,592

DESIGN FOR A GLASS JAR

Ronald H. Dallas, Southgate, Calif., assignor to
Glass Containers, Inc., Los Angeles, Calif., a
corporation of California

Application December 27, 1937, Serial No. 73,874

Term of patent 7 years

To all whom it may concern:

Be it known that I, Ronald H. Dallas, a citizen
of the United States, residing at Southgate, in
the county of Los Angeles and State of Cali-
fornia, have invented a new, original, and orna-
mental Design for a Glass Jar, of which the fol-
lowing is a specification, reference being had
to the accompanying drawing, forming part
thereof.

Fig. 1 is a face view of the glass jar showing
my new design;

Fig. 2 is an edge view; and

Fig. 3 is a top plan view thereof.

The side of the jar opposite from Fig. 1 is
identical with Fig. 1, and the edge of the jar op-
posite from Fig. 2 is identical with Fig. 2.

I claim:

The ornamental design for a glass jar as shown
and described.

RONALD H. DALLAS.
